UNITED STATES PATENT OFFICE.

JOSEPH T. CRABBS, OF BROOKLYN, NEW YORK.

APPARATUS FOR TABULATING THE PASSENGER TRAFFIC ON CAR-LINES.

959,313.

Specification of Letters Patent.

Patented May 24, 1910.

Application filed January 13, 1910. Serial No. 537,954.

To all whom it may concern:

Be it known that I, JOSEPH T. CRABBS, a citizen of the United States, residing at Brooklyn, in the county of Kings and State 5 of New York, have invented certain new and useful Improvements in Apparatus for Tabulating the Passenger Traffic on Car-Lines; and I do hereby declare the following to be a full, clear, and exact description 0 of the invention, such as will enable others skilled in the art to which it appertains to make and use the same.

My invention relates to apparatus for tabulating the passenger traffic on a car line, 15 and the object of the invention is to record graphically the relation between the available seats, and the passengers carried by a given car line at any given point.

It becomes important in practice to determine the relative number of passengers 20 carried as compared with the seating capacity of the cars at various times of the day. Thus during the rush hours it is important to ascertain what number of cars 25 are required to carry the heavy loads, while during the slack hours of the day it is important, as far as practicable, to dispense with any excess of cars. The idea being to apportion the cars according to the varying 30 requirements of the traffic, in the herein described apparatus, I provide means for graphically indicating the difference between the seating capacity of the cars and the number of passengers carried by said 35 cars.

My invention will be understood by reference to the accompanying drawings, in which the same parts are indicated by the same letters throughout the several views.

Figure 1 is a plan view, full size, of the instrument, parts being broken away. Fig. 2 is a side elevation as seen from the right of Fig. 1. Fig. 3 shows a section along the line 3—3 of Fig. 1. Fig. 4 is a perspective view of one of the sliding rods carrying a punch and pointer. Fig. 5 shows a modification in which two punches are carried by the same sliding bar. Fig. 6 is a detail showing the paper used in the apparatus. 40 Figs. 7 and 8 show modifications in which a copying ribbon and keys are used instead of the punch of the previous figures. Fig. 9 shows another modification in which a pencil is inserted in a sliding block and is 45 caused to make a mark on the paper, and

Fig. 10 shows the paper marked with the pencil, as shown in Fig. 9.

A represents a casing which is preferably provided with glass panels α on top and with a door α' at the back, hinged as at α^2 60 and fastened as at α^3 , see Fig. 3. Next to the glass panels α are the scales B and C, separated by a slot, as shown in Fig. 1. On the scale B the normal seating capacities of the various types of cars are marked. 65 Thus let us assume that the various types of cars running on any given line have the seating capacities, respectively, of thirty, forty eight, sixty and sixty five persons, as shown on the scale B. The scale C is calibrated from 0 to 100 to correspond with the 70 rulings on the paper D, which is passed beneath the glass panels α and is wound on the drums E and E', as shown in Figs. 1 and 3. These drums are preferably slotted, 75 as at e , to permit the insertion of the edge of the paper which is then wound on said drum, as shown. This paper is passed through the slot h of the sliding bar H, as shown in Fig. 3, and this record paper is 80 ruled to correspond to the graduations on the scales C and B, the ordinates indicating the passenger capacity, and the abscissæ indicating the time interval. Thus by reference to Fig. 6 it will be noted that the horizontal lines used to note the number of passengers are numbered from 0 to 100, while the vertical lines used to indicate the time 85 interval are marked every ten minutes. Of course the paper may be marked to indicate 90 minute intervals, or less, if desired. In the form of device shown in Figs. 1 to 4, two bars H are arranged to slide in the casing, each slotted as at h to permit the passage 95 through the record paper, and each bar carrying the punch I, whose end i projects into the die h^0 . The punch is normally restored to the initial position by means of the spring i' . There are two of these punches I and I', each on its bar H and H', and each 100 punch carries a pointer i^2 and i^3 traveling over the corresponding scales B and C, as shown in Fig. 1. Each drum E is turned by means of a milled head E^2 , and to prevent lost motion a friction bearing is provided, 105 as shown, for instance, in Fig. 1, in which the end e^2 of the shaft of the drum bears against the spring f which is held under compression by the thumb nut F.

In practice the observer holds the instru- 110

ment in one hand and turns the paper from time to time so that the proper time may be indicated beneath the glass cover. As each car passes the observer moves the punch I so that its pointer will point to the normal seating capacity of the car indicated on the scale B. The observer will, of course, know the normal seating capacity of each type of car used on the line. Having moved the 10 pointer i^2 to the position indicated, he punches a hole in the paper indicated by one of the larger circles in Fig. 6. Now the observer estimates the number of passengers carried by said car and moves the pointer i^3 to the estimated number of passengers indicated by the scale C. He then operates the punch I' and makes one of the small circles shown in Fig. 6. The distance between the small circle and the large circle 15 punched out of the paper will show the difference between the seating capacity of the car and the number of passengers carried by said car, and if the observer keeps turning the paper so that the time interval will be 20 punched out of the paper will show the difference between the seating capacity of the car and the number of passengers carried by said car, and if the observer keeps turning the paper so that the time interval will be 25 approximately shown he will make graphic record of the number of cars, the seating capacity of the cars, and the number of passengers carried by said cars, and this record will show graphically whether the 30 loads on the cars are too heavy or too light, and whether more or less cars are needed at the time of the observations. By taking a series of observations during the entire day, the traffic at any given point will be 35 graphically indicated for that day, and obviously records may be made of the traffic for different days of the week, month, &c.

Referring to Fig. 6, it will be seen that the car passing about 6.20 a. m. had a seating capacity of sixty and had about seventy five passengers on board, also that the car passing about 6.30 had a seating capacity of say forty five and carried seventy passengers, while the car passing about 6.40 had a seating capacity of sixty and only had about thirty five passengers on board.

Instead of using two bars, as shown in Figs. 1, 2 and 4, a single bar having two punches I^2 and I^3 may be used, as shown in 50 Fig. 5, or instead of using punches, keys carrying letters or other characters may be used, as shown in Figs. 7 and 8. In these figures M represents a block carrying a key I^4 , which block is secured, as at m, to slide 55 between the scales B and C. N represents a carbon ribbon which is wound over the drums O and O', as by means of the handle o, and P represents a platen beneath the ribbon. Two of these keys I^4 and I^5 are used, 60 one to indicate the seating capacity of the car, and the other the number of passengers carried by the car.

In the modification shown in Fig. 9, the block Q is grooved as at q, to slide over the 65 scales B and C, and is provided with oppo-

sitely disposed pointers i^2 . This block is perforated, as at q', to receive the end of the pencil R, the block is moved until the pointer i^2 indicates the seating capacity of the car, then the pencil is inserted and the block is moved until the other pointer indicates the estimated number of passengers on the car. 70

The line marked on the paper D by the pencil will show the difference between the number of passengers carried, and the seating capacity of the car, and by using one color of pencil to indicate when the load is greater than the seating capacity, and another color of pencil when the seating capacity is greater than the load, a graphic representation of the condition of the traffic may be secured. Thus, by referring to Fig. 10, if the line S be made with red pencil it would indicate that in a car having a seating capacity of fifty there were thirty passengers standing, while if the line S' be made with a blue pencil it would indicate that in a car having a seating capacity of fifty five there were twenty five passengers only, leaving seats available for thirty persons. 80

It will be obvious that various other modifications may be made, in which the same general idea may be carried out of producing a visual record of the difference between the seating capacity of the various cars and 95 the passengers on said cars.

Having thus described my invention, what I claim and desire to secure by Letters Patent of the United States is:—

1. An apparatus of the character described comprising a paper holder adapted to carry a strip of ruled paper, provided with graduations to indicate elements of time, and other graduations to indicate numerals, means for moving said strip of paper, means for making two sets of marks on said paper, and two calibrated scales to guide said mark making means, substantially as described. 100

2. An apparatus of the character described comprising a paper holder adapted to carry a casing, a strip of paper movably mounted in said casing and provided with a series of graduations arranged in rectangular form, scales mounted in front of said paper, pointers traveling along said scales, and means for marking on said paper the position of the respective pointers, substantially as described. 110

3. An apparatus of the character described comprising a paper holder adapted to carry a strip of ruled paper, provided with graduations to indicate elements of time, and other graduations to indicate numerals, means for moving said strip of paper, punches for making two sets of marks on said paper, pointers carried by said punches, and two calibrated scales beneath said pointers, substantially as described. 125

4. An apparatus of the character described comprising a paper holder adapted to carry a casing, a strip of paper movably mounted in said casing and provided with 5 a series of graduations arranged in rectangular form, the abscissæ to indicate elements of time, the ordinates to indicate numbers of passengers, scales mounted in front of said paper, pointers traveling along said 10 scales, and means for marking on said paper the position of the respective pointers, substantially as described.

5. An apparatus of the character described comprising a paper holder adapted 15 to carry a strip of ruled paper, provided with abscissæ graduated to indicate elements of time, and ordinates graduated to indicate numbers of passengers, means for moving said strip of paper, and means for 20 making two sets of marks on said paper, substantially as described.

6. An apparatus of the character described comprising a paper holder adapted to carry a strip of ruled paper, provided 25 with abscissæ graduated to indicate elements of time, and ordinates graduated to

indicate numbers of passengers, means for moving said strip of paper, means for making two sets of marks on said paper, and two calibrated scales to guide said mark 30 making means, whereby a visual record is made to indicate the difference between the seating capacity and the passenger load, substantially as described.

7. An apparatus of the character described comprising a paper holder adapted to carry a casing, a strip of paper movably mounted in said casing and provided with a series of graduations arranged in rectangular form, two scales mounted in front of 40 said paper, pointers mounted between and traveling along said scales, and means for marking on said paper any given position of the two pointers, respectively, substantially as described. 45

In testimony whereof, I affix my signature, in presence of two witnesses.

JOSEPH T. CRABBS.
